UNITED STATES PATENT OFFICE.

MAHLON L. DUNBAR, OF NORWALK, OHIO.

FIRE-EXTINGUISHING APPARATUS FOR VEHICLES.

Application filed May 11, 1918, Serial No. 233,956. Renewed January 18, 1924.

To all whom it may concern:

Be it known that I, MAHLON L. DUNBAR, a citizen of the United States, residing at Norwalk, in the county of Huron and State 5 of Ohio, have invented new and useful Improvements in Fire-Extinguishing Apparatus for Vehicles, of which the following is a specification.

This invention relates to fire extinguishing 10 apparatus for vehicles, the object in view being to provide means capable of quick and manual control whereby a fire extinguishing chemical, under pressure, may be distributed, scattered or sprayed around a predetermined danger zone, as, for example, the engine compartment or space of an airplane, motor vehicle, motor boat, or the like.

The present invention is designed primarily for use in conjunction with the engine and engine compartment of an airplane or any other type of aircraft in which by reason of the high test fuel employed, there is special danger of fire produced from various causes, such, for example, as a back 25 fire from the engine. It is to be understood, however, that the invention is designed to be used in conjunction with any danger zone in a motor driven vehicle, as, for example, the gasoline or fuel tank and it will 30 be apparent as the description proceeds, that several danger zones in the same aircraft or other vehicle may be subjected simultaneously to the smothering action of the fire extinguishing chemical.

Another object of the invention is to provide means under the same control as the fire extinguishing apparatus for preventing air from reaching the danger zone, said means being shown in the form of a shutter 35 which is closed simultaneously with the beginning of the operation of the fire extinguishing apparatus, and which is again opened as soon as the operation of the fire extinguisher terminates.

With the above and other objects in view, the invention consists in the construction, combination and arrangement of parts, as herein described, illustrated and claimed.

In the accompanying drawings:

Figure 1 is a plan view showing the fire extinguishing apparatus in its applied relation to the engine compartment and the driver's compartment of a vehicle, such as an airplane or motor vehicle.

Figure 2 is a detail perspective view of the distributing spray pipe.

Figure 3 is a fragmentary cross section through the spray pipe.

Figure 4 is a detail view of the shutter 20.

In order to illustrate the application and use of the fire extinguishing apparatus of this invention, I have shown a portion of a motor driven vehicle, comprising an engine compartment 1 and a driver's compartment 2. The hood or cover of the engine compartment is omitted in Figure 1 in order to illustrate the engine which is conventionally shown at 3, 4 designating the radiator used in conjunction with the engine and 5 the instrument board or dash of the vehicle. 70

The fire extinguishing apparatus comprises a compressed air cylinder 6, a chemical cylinder 7 and a controlling valve 8 arranged in a conduit between the cylinders 6 and 7 and operable by means of a handle 9 which is within easy and convenient reach of the operator of the vehicle. Leading off from the cylinder 7 is an outlet or discharge pipe 10 which is controlled by a valve 11 connected by a rod 12 or the equivalent thereof with an arm 13 on the stem of the valve 8 whereby both of said valves 8 and 11 are operated simultaneously, one to release the air and the other to release the fire extinguishing chemical which is propelled by compressed air. 75

The outlet or discharge pipe 10 extends into the engine compartment 1 which constitutes a danger zone in which the engine 3 operates. In the form of the spray pipe shown in Figures 1 and 2, said pipe is generally rectangular in shape or formation, comprising the opposite and substantially parallel portions 14 and 15, the opposite and substantially parallel end portions 16 and 17 and a T-coupling 18 to which the pipe 10 is attached. The side portions 14 and 15 are shown as offset upwardly from the main portions 16 and 17 to obtain a better distribution of the chemical throughout the danger zone or engine compartment. 90

The spray pipe, as a whole, is formed with a multiplicity of perforations 19, as shown to enable the fire extinguishing chemical to be distributed and sprayed throughout the entire danger zone or engine compartment. It is obvious, however, that the shape or formation of the spray pipe may be changed at will in accordance with any special requirements such as danger zones of 95

different shapes, sizes, dimensions and the like. 110

2
While the invention has been particularly designed for use in conjunction with aircraft in general, it will, of course, be understood that the apparatus may, with equally good results, be used in conjunction with any danger zone of any motor driven vehicle, the broad object in view being to provide fire extinguishing apparatus which may be used effectively in the manner above described in a motor driven vehicle while the latter is in motion. The apparatus is particularly useful in an aircraft where the high speed of the machine and the frequent impossibility of making a quick landing precludes the extinguishing of a fire and results in the fire making fatal progress before the life or lives of the occupant or occupants of the vehicle may be saved.

In order to render the apparatus still more effective for aerial and automobile purposes, a shutter 20 may be arranged adjacent to and preferably in front of the radiator 4 and operatively connected by means at 20^a with the handle 9 so that when the handle 9 is moved in the direction to set the fire extinguishing apparatus in operation, the shutter 20 will be concurrently closed, and on the other hand when the handle 9 is moved in the opposite direction and the fire extinguishing apparatus is cut off, the shutter 20 will again be simultaneously opened. By thus excluding

oxygen or fresh air from the danger zone, the smothering of the fire is insured. In some cases, it will only be necessary to extend a portion of the spray pipe in front of the engine or head of the engine in the direction in which the aircraft is being propelled in which case, as soon as the chemical is sprayed from said pipe, it will be swept rearwardly over the danger zone through the engine compartment by the inpouring air which passes through the radiator 4.

I claim:—

In combination, a motor vehicle, a manually-controlled source of chemical supply under pressure carried by the motor vehicle as part of the equipment thereof, a motor carried by the vehicle also as part of the equipment thereof, a spray pipe connected with said source and surrounding and adapted to deliver the chemical over the area in which the motor is located, the manual controlling means being located within convenient reach of the operator, and a movable shutter in front of the motor and the said area in which the motor is located to prevent the admission of air to the area and motor during the time that the chemical is supplied to the said area and operable by the manual means for controlling the chemical supply.

In testimony whereof I affix my signature.
MAHLON L. DUNBAR.
